Baldwin & Wright

UNITED STATES PATENT OFFICE.

HENRY SKINNER, OF ROSHerville, ENGLAND.

MIXING MACHINERY.

No. 838,542.

Specification of Letters Patent.

Patented May 26, 1908.

Application filed May 10, 1907. Serial No. 372,884.

To all whom it may concern:

Be it known that I, HENRY SKINNER, engineer, a subject of the King of Great Britain, residing at Ann's Villa, Beresford Road, 5 Rosherville, in the county of Kent, England, have invented new and useful Improvements in Mixing Machinery, of which the following is a specification.

For mixing slurry and other fluids I employ a vertical revolving cylinder open at its ends and for the most part but not completely immersed in the fluid to be mixed. Within the interior of the cylinder is fixed a double threaded screw and around the lower part of 10 the outside of the cylinder another double threaded screw. One screw is made right handed and the other left handed. The outside screw drives the fluid downwards and the inside one draws it up through the open lower end of the cylinder and discharges it 15 from the upper end which is made bell mouthed so that the discharged slurry may be caused to drop back into the tank at some distance from the cylinder. Radial baffle 20 plates standing up from the bottom of the tank just clear of the outside screw may also be used.

The tank may be circular and made concave at the bottom and the vertical screw 25 cylinder be mounted in the center of the tank or for larger sizes the tank may be of annular form with a similar concave bottom and a number of revolving screw cylinders formed as above described be used at equal 30 distances apart. The shafts of the cylinders may also be supported by arms extending from a shaft concentric with the tank and slowly revolved so that in addition to each cylinder being made to revolve on its own 35 shaft it is also caused to travel around the annular tank.

Figure 1 is a vertical section of a mixing machine in which the vertical cylinder with its exterior and interior screw threads is 40 mounted centrally within a circular tank having a concave bottom as above described. Figs. 2 and 3 are vertical sections of the cylinder one showing one portion of the inner and outer screw threads and the other the 45 other portion. Fig. 4 is a vertical section showing a pair of such revolving vertical cylinders mounted within a tank of annular form. Fig. 5 is a vertical section and Fig. 6 50 a side elevation of one of the vertical cylinders.

In Figs. 1, 2 and 3 A is the tank, B the

vertical cylinder, C the inner screw threads and D the outer screw threads. The screw-threads C constitute what I call the screw-threaded propeller for the inside of the cylinder and the screw-threads D constitute the screw-threaded propeller of the outside of the cylinder. E E are fixed radial baffle plates. The arrows indicate the directions in which the slurry is propelled.

In the modification shown in Fig. 4 the vertical shafts of the cylinders are shown to be supported at opposite ends of a girder F which is capable of being turned around a central shaft G concentric with the tank. 60 The vertical shafts of the cylinders are as shown driven from a shaft H extending along the girder. The girder is made to turn slowly round the shaft G by a pinion I carried by it gearing with a fixed toothed wheel J. The pinion I and shaft H may be driven by any suitable motor carried by the central portion of the girder.

As seen in Fig. 6 the lower end of the vertical shaft of each revolving cylinder may be 65 made to carry a loose baffle blade K. This blade would not be revolved with the vertical shaft but would remain trailing behind it as the shaft was made to travel slowly around the annular tank.

As indicated in the drawings by dotted lines the liquid forced up through each cylinder is by the revolution of the cylinder thrown outwards from it at the top in a dome like stream.

What I claim is:

1. In machinery for mixing liquids, the combination of a tank, a vertical cylinder open at both ends within the tank, and having its lower end a short distance above the bottom thereof, a screw-threaded propeller carried within the lower part only of the interior of the cylinder, and means for revolving the cylinder in a direction to cause the propeller to force the liquid upwards through the cylinder and to throw the liquid laterally from the upper end thereof.

2. In machinery for mixing liquids, the combination of a tank, a vertical cylinder open at both ends within the tank, having 105 its lower end a short distance above the bottom thereof and having a bell mouthed top, a screw-threaded propeller carried within the lower part only of the interior of the cylinder, and means for revolving the cylinder in a 110 direction to cause the screw-threads to force the liquid upwards through the cylinder and

to throw said liquid laterally from the upper end of the cylinder.

3. In machinery for mixing liquids, the combination of a tank, a vertical cylinder within the tank which is open at both ends and has its lower end a short distance above the bottom of the tank, portions of screw-threads within the lower part only of the interior of the cylinder, and portions of screw-threads around the lower part of its exterior, the pitch of said screw-threads being opposite, and means for driving the cylinder with said screw-threads in a direction to cause the outer screw-threads to drive the liquid downwards and the inner screw-threads to drive it upwards.

4. In machinery for mixing liquids, the

combination of a tank, a central vertical shaft, horizontal arms above the tank free to turn slowly around the vertical shaft, a vertical spindle carried by each arm, a vertical cylinder open at both ends mounted on each vertical spindle and having its lower end a short distance above the bottom of the tank, portions of screw-threads carried within the lower part of the exterior of the cylinder, and means for revolving the cylinder in a direction to cause the screw-threads to drive the liquid upwards through the cylinder.

HENRY SKINNER.
